John E. Earle

United States Patent Office.

F. B. MORSE, OF NEW HAVEN, CONNECTICUT.

Letters Patent No. 80,202, dated July 21, 1868.

IMPROVEMENT IN STUMP-JOINT FOR CARRIAGES.

The Schedule referred to in these Letters Patent and making part of the same.

TO ALL WHOM IT MAY CONCERN:

Be it known that I, F. B. MORSE, of New Haven, in the county of New Haven, and State of Connecticut, have invented a new Improvement in Stump-Joint for Carriages; and I do hereby declare the following, when taken in connection with the accompanying drawings, and the letters of reference marked thereon, to be a full, clear, and exact description of the same, and which said drawings constitute part of this specification, and represent, in—

Figure 1, a side view of the joint closed,

Figure 2 an end view of the same,

Figure 3 a central section of the joint closed, and in

Figure 4 a like section, the joint open.

This invention relates to an improvement in the article of manufacture commonly called "stump-joint for carriages," that is to say, the joint which unites the parts of the braces which support the top of the carriage, and by means of which the top may be dropped at pleasure. The object of the invention is to simplify the construction, and produce a strong and durable article at a comparatively small cost. To this end the invention consists in forming a recess in the meeting ends of the joint, and placing therein a link or hinge-plate, of a form corresponding to the recess in the joint, so that, when open or closed, the plate and parts of the joint come to a firm bearing, so as to prevent the joint from becoming "shackly" by constant use.

In order to the clear understanding of my invention, I will fully describe the same as illustrated in the accompanying drawings.

A is the one part, B the other, usually formed from square metal, of the size proportionate to the style of carriage for which it is intended. In the end of each of the parts A and B, I form a recess, as denoted in figs. 2 and 3, and in order to do this by machinery, I form the recess in each of a quarter circle, so that a milling-tool, of the proper diameter, will cut the recess of the proper form, the centre of the circular cut being at the inner meeting angle of the two parts; then, at a point, a, in each, equidistant from the inner edge and end, I bore through for the pivot. C is the connecting, or hinge-plate, formed so that rivets d will pass therethrough, and the said plate of such form that when the two parts are closed, as in fig. 3, the edge of the plate C will bear against the slot in both parts, as at f, fig. 3, and thus prevent any movement or "end thrust" of the two parts, and also that when the two parts are open, as in fig. 4, the opposite side of the plate C will strike the slot in the two parts at h, (see fig. 4,) and in like manner support the two parts in a fixed rigid position.

The inner angle of the two parts should be rounded, taking the pivot as a centre, so that the parts will open one upon the other. This portion of the parts A and B being cut away, affords room for the shaft of the cutter, which forms the slot in the end of the parts.

The plate C is cut from a plate of suitable metal by a die of the proper form, and punched, so that the expense of fitting the plate is very trifling.

Upon the outer and opposite sides of the two parts I place round plates or buttons D, through which pivots d pass and are riveted, so as to secure the buttons in their place, thereby forming a support to the parts, as well as an ornament at the joint.

Having thus fully described my invention, what I claim as new and useful, and desire to secure by Letters Patent, is—

1. A stump-joint, consisting of the two parts A and B, joined by the plate C and pivots d, when the said plate C is arranged and fitted into the parts A and B, so as to operate in the manner specified.
2. In combination with a stump-joint, I claim the buttons or plates D, arranged upon opposite sides of the joints, substantially in the manner herein set forth.

F. B. MORSE.
